Primary Examiner — Jennifer Rivard

(57) CLAIM

The ornamental design for a compact, as shown and described.

DESCRIPTION

FIG. 1 is a perspective view of a compact in accordance with my new design;

FIG. 2 is a front view thereof;

FIG. 3 is a rear view thereof;

FIG. 4 is a left view thereof;

FIG. 5 is a right view thereof;

FIG. 6 is a top view thereof;

FIG. 7 is a bottom view thereof; and,

FIG. 8 is another perspective view thereof in a partially separated state.

The broken lines illustrate portions of the compact and form no part of the claimed design.
